(57) **CLAIM**

The ornamental design for a portion of a multi-handled bag, as shown and described.

DESCRIPTION

FIG. 1 is a perspective view of a portion of a multi-handled bag showing our new design;
 FIG. 2 is a top view thereof;
 FIG. 3 is a perspective view of another embodiment thereof;
 and,
 FIG. 4 is a perspective view of a further embodiment thereof.

The uneven broken lines in the center portion of each bag shown in FIGS. 1-4 represent an unclaimed boundary of the design. The even broken lines within the end flaps of FIGS. 1-3 indicate a perforation appearance, and the solid curved line within the end flap of FIG. 4 indicates a cut-line appearance.
